CONTROL PANEL FOR A LAUNDRY MACHINE

Henrik Langhjelm, Pontiac, and Montgomery Ferar,
Huntington Woods, Mich., assignors to Whirlpool Corporation,
a corporation of Delaware

Filed Apr. 10, 1961, Ser. No. 64,665

Term of patent 14 years

(Cl. D49—1)

FIGURE 1 is a front elevational view of a control panel for a laundry machine, showing our new design.

FIGURE 2 is an end elevational view thereof taken from the left of FIGURE 1.

FIGURE 3 is a cross-sectional view taken on line 3-3 of FIGURE 1.

FIGURE 4 is a cross-sectional view taken on line 4-4 of FIGURE 1.

FIGURE 5 is a top plan view thereof.

The end not shown is substantially the same as the end shown and the rear is plain.

We claim:

The ornamental design for a control panel for a laundry machine, as shown and described.
